Attorney—Nilsson & Robbins

ABSTRACT: A safety ladder for use in water in combination with a pile extending above the surface of the water and a floating structure. The floating structure includes means for encircling the pile to be thereby limited in lateral movement. At least one of the side rails is secured to the floating structure and at least one of the side rails is secured to the pile encircling means.

SAFETY LADDER FOR WATER USE

FIELD OF THE INVENTION

The fields of art to which the invention pertains include the fields of ladders and floating structures.

BACKGROUND AND SUMMARY OF THE INVENTION

The increasing popularity of boating as both sport and recreation has resulted in a proliferation of marina facilities. Modern marina construction techniques include the utilization of floating wharf structures to provide inexpensive yet effective land access for boats. The present invention is concerned with a particular aspect of such construction, specifically in providing means for the boater to climb from his boat, or from the water, onto the floating structure. Particularly this invention provides a ladder for use in water which can be secured to a floating structure in such a manner that safety in use of the ladder is insured. The floating structures with which this invention is concerned are constructed so as to engage a pile extending above the surface of the water to be thereby limited in lateral movement, and the ladder is attached to the structure in close proximity to the pile. At least one of the side rails of the ladder is secured to the floating structure and the same and/or opposite side rail is secured to the pile encircling means. A forward portion of at least one of the rails extends above the surface of the floating structure to constitute a handrail spaced from the surface and a return portion extends rearwardly and downwardly from the handrail portion to the point of securing to the pile encircling means.

In one form of the invention, the floating structure includes a floating platform and the pile encircling means comprise an annular member disposed around the pile and secured on one side to the platform. With this structure, one only of the rails is secured to the floating platform and the other of the rails is secured to the annular member. In another form of the invention, the pile encircling means is constituted by a portion of floating platform which defines an opening therethrough for the pile, and in this embodiment, both side rails of the ladder may be secured to the platform. BRIEF DESCRIPTION OF THE DRAWINGS

FIG. 1 is a side elevation view of one form of ladder of this invention;

FIG. 2 is a front elevation view of the ladder of FIG. 1;

FIG. 3 is a side elevation view of another form of ladder of this invention;

FIG. 4 is a front elevation view of the ladder of FIG. 3; and

FIG. 5 is a partial sectional view on line 5-5 of FIG. 4, in the direction of the arrows.

BRIEF DESCRIPTION

Referring to FIGS. 1 and 2, a ladder, generally indicated at 10, is shown which is designed for use with a floating structure, generally indicated at 12. In this particular illustration, the floating structure 12 includes a plurality of pontoons 14 supporting the platform decking 16 which may be formed of concrete, wood, or other structurally appropriate material, and an annular retaining ring 18 secured to the platform 16. As illustrated, the platform 16 has a facing timber or stringer 20 secured to the outer edge of the platform 16 by bolts or other means (not shown). The annular ring 18 is secured on one side thereof, at 22, by welding or other means to an angle iron, which, in turn, is secured to the facing 20 by means of bolts 26 therethrough. A pile 28 or piling extends above the surface of the body of water 30 and the annular member 18 is disposed about the pile 28 as a pile ring and serves to limit lateral movement of the floating structure 12. As shown in section, at 32, in FIG. 2, the pile ring 18 is of tubular structure, in this case formed of 1½-inch galvanized pipe.

The ladder 10 consists of a relatively short side rail 34 (FIG. 2), a relatively long side rail 36 and a plurality of rungs 38 secured to and between the side rails 34 and 36. The short side rail 34 is secured at its upper end to the angle iron 24 by weld-

ing thereto, as indicated as 40 in FIG. 2, or by other means (in the drawing, a portion of the upper end of the short rail 34 is cut away for a more detailed view of the pile ring 18 connection to the angle iron 24). The longer side rail 36 is formed

5 with an upper forward portion 42 thereof extending rearwardly above the surface of the platform 16 to constitute a handrail portion 44 spaced from that surface, and is further formed with a return portion 46 (FIG. 1) extending rearwardly and downwardly from the handrail portion 44 to the pile ring 18 where it is secured to the pile ring by welding as at 48, or by other means. Both side rails 34 and 36 are tubular in structure and formed in this case of 1½-inch galvanized pipe.

Referring now to the rungs 38, each is formed of 1-inch by 10 -inch oak members 50 secured to angle irons 52 by means of 15 ¼-inch brass bolts 54, and nuts 56, as shown. The oak members 50 are secured to the side rails 34 and 36 as crosspieces, by welding of the angle irons 52 as at 58, or by other means, so as to constitute a ladder.

20 The ladder structure described hereinabove is thus secured at two spaced locations along substantially the same horizontal plane and the particular arrangement depicted imparts a high degree of rigidity to the ladder. Added safety is obtained by the provision of the two-spaced points of attachment at locations on the floating structure immediately adjacent the pile 28, and this proximity to the pile 28 effects a high degree of stability and reliability to the ladder 10 in that lateral movements of the ladder are more highly restricted at that location than at other locations. At other locations, particularly with a 25 floating structure of modest size, lateral forces generated by one attempting to mount the ladder would tend to move the floating structure, making mounting of the ladder difficult and hazardous.

30 FIGS. 1 and 2 depict a ladder constructed to extend outwardly from one side of the platform. Referring now to FIGS. 3, 4 and 5, another form of the invention is illustrated wherein a ladder 60 is constructed so that both sides thereof bear against the side of the floating structure 62. The floating structure 62 includes a platform and facing timbers 64, 66 and 68 supported by one or more pontoons 70 on a body of water 72.

35 In this embodiment, the floating structure 62 includes an expanse of wooden decking 74 (FIG. 5) which is formed so as to define an opening 76 therethrough adjacent one edge and through which a pile 78 extends to thereby limit lateral movement of the floating structure 62.

40 A weld plate 80 is bolted to the decking surface 74 rearwardly of the opening 76 and angle irons 82 and 84 are bolted to the forward facing timber 66. These components serve to secure the ladder 60 to the floating structure 62. Specifically, 45 the ladder 60 is constituted of a single continuous tubular member of 1½-inch galvanized pipe bent to form opposed side rails 86 and 88 which are secured at intermediate points to the angle irons 82 and 84 by welding, as at 90 and 92, and which extend upwardly from the surface of the decking 74 to form handrail portions 94 and 96. The tubular member is formed rearwardly and downwardly from the handrail portions 94 and 96 around the pile 78 to a generally U-shaped portion 98 and is secured at that portion 98 to the weld plate 80 by welding, as at 100, or by other means.

50 55 The forward portions of the tubular member constituting the side rails 86 and 88 are interconnected by rungs 102 which are formed and secured in the manner described above with respect to the ladder 10 of FIGS. 1 and 2. The ladder 60 depicted in FIGS. 3-5 is thus seen to be secured at several spaced points about the pile 78 so as to provide a ladder which is limited in lateral movement and which is strongly secured to the floating structure.

I claim:

1. A ladder for use in water in combination with: a pile extending above the surface of the water; a floating structure including means for encircling said pile to limit lateral movement of said floating structure; said ladder comprising side rails and a plurality of rungs; at least one of said side rails being secured to said floating structure; and

at least one of said side rails being secured to said pile encircling means.

2. The invention according to claim 1 in which at least one of said rails includes a portion extending above the surface of said floating structure to constitute a handrail spaced from said surface.

3. The invention according to claim 1 in which said rail fixed to said pile encircling means includes a forward portion extending above the surface of said floating structure to constitute a handrail spaced from said surface, and a return portion extending rearwardly and downwardly from said spaced handrail portion to the securing point of said pile encircling means.

4. The invention according to claim 1 in which said floating structure includes a floating platform and said pile encircling means comprises an annular member disposed around said pile and secured on one side to said platform.

5. The invention according to claim 1 in which one only of said rails is secured to said floating structure and the other of said rails is secured to said pile encircling means.

6. The invention according to claim 1 in which:
said floating structure includes a floating platform;
said pile encircling means comprises an annular member disposed around said pile and secured on one side to said platform;
one only of said rails is secured to said platform; and

the other of said rails is secured to the other side of said annular member.

7. The invention according to claim 6 in which said other rail includes:

a forward portion extending above the surface of said platform to constitute a handrail spaced from said surface; and

a return portion extending rearwardly and downwardly from said spaced handrail portion to the securing point on said annular member.

8. The invention according to claim 1 in which said floating structure includes a floating platform and said pile encircling means is constituted by a portion of said platform defining an opening therethrough for said pile.

9. The invention according to claim 1 in which said side rails are defined by opposed legs of a single continuous bent member.

10. The invention according to claim 1 in which both side rails are secured to said floating structure and each includes:

a forward portion extending above the surface of said floating structure to constitute a handrail spaced from said surface; and

a return portion extending rearwardly and downwardly from said spaced handrail portion to the securing point of said pile encircling means.
